UNITED STATES PATENT OFFICE.

CHARLES A. FLEMING, OF JACKSON, MICHIGAN, ASSIGNOR, BY DIRECT AND MESNE ASSIGNMENTS, OF ONE-HALF TO BRISCOE DEVICES CORPORATION, OF PONTIAC, MICHIGAN, A CORPORATION OF MICHIGAN, AND ONE-HALF TO THOMAS D. BUICK, OF DETROIT, MICHIGAN.

CARBURETOR.

Application filed October 1, 1917. Serial No. 184,152.

To all whom it may concern:

Be it known that I, CHARLES A. FLEMING, a citizen of the United States, residing at Jackson, county of Jackson, State of Michigan, have invented a certain new and useful Improvement in Carburetors, and declare the following to be a full, clear, and exact description of the same, such as will enable others skilled in the art to which it pertains to make and use the same, reference being had to the accompanying drawings, which form a part of this specification.

My invention relates to carburetors and objects of my improvements are to supply a uniform mixture to an internal combustion engine at all speeds to provide a device that shall not clog in use and one in which there is a variable passage for liquid fuel the maximum supply thru which is adjusted.

I secure these objects in the invention illustrated in the accompanying drawing, in which;

Figure 1 is a sectional elevation of a carburetor embodying my invention.

Figure 2 is a detail sectional view of the adjustable plug.

Figure 3 is a section on the line C—C Fig. 2.

Figure 4 is a section on the line D—D Fig. 2.

Figure 5 is a sectional detail view showing the adjustable plug and socket, the former being shown in full lines.

Fig. 6 is a section of a plug c on the line VI—VI, Fig. 1, looking from the right of said figure.

Fig. 7 is a plan view of the valve e. a indicates the carburetor casing as a whole. The air enters the passage there thru at a² and leaves the casing on the engine suction side at a³. a⁴ is the reservoir for liquid fuel. There is a cylindrical part b depending from the wall of the air passage which is hollow to form the passage b² thru which the fuel is fed from the reservoir a⁴ to the air passage. A drain cock is provided for the passage b², as shown in Fig. 1.

The passage b² is bored out smoothly at its upper end for fitting therein an adjustable plug c which may slide longitudinally in said passage. There is a passage c²

formed thru the plug c which has an adjustable opening at c³ communicating at this point with the air passage thru the carburetor or mixing chamber. The plug c is flattened or cut away as shown at c⁴ upon the side toward the engine intake. This presents a flat wall that converges downward away from the vertical and is terminated by a shoulder c⁵. c⁶ is an opening extending thru the wall of the plug c communicating with the passage therethru and with the lower and deeper portion of the cut away part c⁴.

The construction of the plug c is such that when in its lower position, as indicated in dotted lines in Fig. 1, the passage b² is completely closed except for the passage through said plug and as the plug c is raised, there is a continually enlarging opening at the upper end of the passage b² at d between the wall of the passage b² and the wall of the cut away portion c⁴ of the plug. The aperture c⁶ is of the required size to permit of the passage of the maximum quantity of fuel that will be required at this point by the use to which the particular kind of carburetor is to be put.

e is a valve located in the air passage thru the carburetor and pivoted at e² at its lower edge. e³ is a web extending across the passage and in the normal position of the valve e this web and valve nearly close the air passage. When the engine begins to operate, air is drawn into the passage and oscillates the valve e about its pivot e² thus withdrawing it proportionally from its obstructing position and allowing a greater area of passage for the air.

The valve e is provided with lugs w, w engaging in a slot in the upper end of the plug c so that as said valve is turned about the pivot e² the plug c is thereby raised to a distance proportional to the turning of the valve about its pivot and therefore to the area of opening of the passage.

The operation of the above described device is as follows:

When the engine is first started the suction draws the fuel thru the opening c³. As the suction increases the valve e is turned about its pivot e² and the plug c is raised thereby thus opening a passage for liquid fuel at d which continually enlarges as the

2
plug c rises and as the demand for fuel increases. But the passage thus formed is limited as a maximum by the selected size of the aperture c^o thru the wall of the plug c^2 .

What I claim is:

A carburetor casing having a carbureting chamber therein and adapted to communicate with the atmosphere, a float chamber constantly in communication with the carbureting chamber and adapted to provide a constant supply of volatile fluid for engine idling purposes, a metering pin establishing

communication between the float chamber and the carbureting chamber and having a groove in the wall thereof establishing an additional communication between said float chamber and said carburetor chamber for variable speeds of an engine, and means carried by said metering pin causing air to travel transversely of the direction of the flow of fuel to lift the fuel from said metering pin.

In testimony whereof, I sign this specification.

CHARLES A. FLEMING.
